UNITED STATES PATENT OFFICE

2,119,148

CONTAINER FOR CONFECTIONS

Kostas Bastas, Ottawa, Ontario, Canada

Application October 2, 1936, Serial No. 103,662
In Canada September 11, 1936

1. Claim. (Cl. 229—2.5)

My invention relates to a plate for pie, cake or other confections.

My invention relates more particularly to a unit plate and lid, the lid having an aperture which may be closed or sealed by a sheet of transparent material. The unit may be made of any material, as, for instance, metal, compressed paper, or pulp, and may be made to any shape, as, for instance, square, rectangular, or circular, depending upon the shape which the confection is to assume. For purposes of illustration only, the unit is shown as applicable to pies.

An object of the invention is to provide a unit confection plate and lid, the lid having an aperture which may be closed or sealed by a transparent sheet whereby the contents of the unit may be viewed without having to raise the lid, thereby protecting to a great extent the confection from dust or other contamination. Such a device finds its application more particularly in restaurants and stores where the confection is usually sold in pieces or segments.

In the drawing, wherein like numerals of reference indicate corresponding parts in the various figures,

Figure 1 is a plan view of the device such as would be made from pressed paper or pulp;

Figure 2 is a section on line 2—2 in Figure 1;

Figure 3 is a section similar to that shown in Figure 2, but showing a slight modification. This form would be applicable to metal units, as well as to paper or the like units.

Referring now by numerals to Figures 1 and 2, the pie plate consists of two parts, the dished member 10, being the pie holder proper, and the lid 11, so connected or hinged together that the lid may be raised. The two parts 10 and 11 may be joined or connected by a narrow member or tongue 14. This form of paper unit lends itself to the manufacture of a unit wherein both parts are integral or permanently joined or connected together. This form may prove more convenient to manufacture than if the parts were made separately.

The lid is formed with an aperture 12, which may be closed or sealed by affixing a sheet of thin, transparent material, such as cellophane or paraffin paper, 13, to the lid. This sheet may be affixed to the lid, either within, or as shown, without. The base or pie holder proper, 10, may be formed with an integral or separate tongue or tab 15, upon which may be stamped, printed, or otherwise applied, a word or words identifying the kind of pie or confection within the holder. This tongue extends from the rim 16 of the holder and is preferably positioned in line with the connection or hinge member 14, aforesaid. It will be appreciated that the use of such a tab bearing pastry-identifying data serves a very useful purpose, in that a plurality of plates may be stacked and so relatively disposed angularly that the tabs are in staggered relationship, to thus enable one to readily see all the tabs and thus identify the contents of the respective plates.

If preferred, and feasible, the word or words identifying the confection may be printed upon the transparent sheet. In any event, it may be desired to provide a tab for the sake of convenience in handling the unit.

In Figure 3, the connection 17 is secured to one of the parts, say, the part 10, and is formed with an upright portion terminating in an outwardly curved end 18. A slot (not shown) is formed in the rim of the lid to receive the member 17. This form lends itself particularly to metal units.

I claim:—

A container for confections and the like comprising a dished circular plate surrounded by a lateral flange, an annular ring overlying the side wall of said plate and having a lateral flange adapted to engage with the flange of said plate, a sheet of transparent material covering the opening of said ring through which the contents of the plate may be viewed, a strap integral with the flanges of said plate and ring hingedly connecting the ring and plate together and a tab projecting from the flange of the plate diametrically opposite the strap.

KOSTAS BASTAS. 45
